CLAIM

The ornamental design for a rolling tube for an air strut, as shown and described.

DESCRIPTION

FIG. 1 is a perspective view of a rolling tube for an air strut according to our invention;

FIG. 2 is a side elevation view thereof;

FIG. 3 is a front and back elevation view thereof;

FIG. 4 is a top plan view thereof; and,

FIG. 5 is a bottom plan view thereof.

The dash-dash broken lines in the drawings illustrate portions of the rolling tube for an air strut that form no part of the claimed design. The dot-dash broken lines in the drawings represent the claim boundary and form no part of the claimed design.

1 Claim, 4 Drawing Sheets(56)
